TIME METER WITH ALARM DEVICE

Raymond Beaumann, Les Bois, Switzerland, assignor to Ebauches S.A., Neuchatel, Switzerland
Filed Aug. 25, 1959, Ser. No. 835,954
Claims priority, application Switzerland Sept. 11, 1958
8 Claims. (Cl. 58—21.13)

The present invention relates to a time meter with alarm device, adapted to produce an alarm signal at the end of a predetermined lapse of time, including a clockwork movement and an alarm device arranged between two pillar plates, a driving member adapted to successively engage a part of the said clockwork movement and a part of the said alarm device, a single main spring arranged outside the frame formed by the said pillar plates and a rotary winding knob, coaxial with the said driving member, serving to wind the main spring and to set the said lapse of time.

According to the invention, the outer end of the main spring is attached to a cap secured to one of the said pillar plates, whereas its inner end is hooked to a pin traversing the shaft of the winding knob and the hub of the driving member, the said pin interlocking the winding knob and the driving member and securing the winding knob in axial direction.

The invention also relates to a method of manufacture of the above-mentioned time meter with alarm device. This method comprises the steps of placing in the frame the driving member and the gears of the clockwork movement and of the alarm device, fixing the pillar plates to each other, placing the winding knob by inserting its shaft into the hub of the driving member, mounting a core on the lower end of the said hub, pushing the pin through the said core, hub and shaft, placing the cap provided with its spring on the lower pillar plate, the cap being guided by bent portions of the said pillar plate, turning the cap so as to hook the inner end of the spring to the said pin, further turning the cap so as to completely stress the main spring, turning back the cap so as to partially release the said spring, fixing the cap by means of a rivet in the angular position obtained, placing the casing formed by a combined back and caseband and a bezel, and calking the bezel on the said combined back and caseband.

The accompanying drawings show, by way of example, one embodiment of the invention.

FIG. 1 is a top plan view of the time meter.

FIG. 2 is an inverted plan view with the back of the casing removed.

FIG. 3 is a top plan view at an enlarged scale, after removal of bezel, winding knob and upper pillar plate.

FIGS. 4 to 6 are cross-sectional views taken along the lines IV—IV, V—V and VI—VI of FIG. 3, respectively.

The frame of the time meter illustrated is formed by two pillar plates 1 and 2, maintained at a distance from each other by means of pillars 3 (FIG. 3). Both pillar plates 1 and 2 have the same shape, but the upper pillar plate 1 has a diameter slightly greater than that of the lower pillar plate 2, as shown in FIGS. 2 and 4.

The time meter consists of a clockwise movement and an alarm device, described hereinafter, all parts of which are pivoted in the pillar plates 1 and 2.

A driving member 4, constituted by a toothed sector, is rigidly secured to a hub 5 pivoted in the pillar plates 1 and 2. The hub 5 is provided with two shoulders 6 and 7 which maintain it in axial direction (FIG. 6). Within the hub 5 is freely mounted a central shaft 8 projecting on both sides of the pillar plates 1 and 2.

At its upper end, the shaft 8 has two lateral lugs 9 which are embedded in the mass of a winding knob 10, made for instance of plastic material. On its top face

2

the winding knob 10 has protuberances 11 adapted to facilitate its seizing with the fingers for rotating it upon winding and setting of the apparatus, and a mark 12. On its lower face the knob 10 has a groove 13 extending over almost one complete turn, which groove is engaged by a lug or bent portion 14 of the upper pillar plate 1 (FIG. 6), the lug 14 forming a stop means limiting the rotary movement of the knob 10.

At its lower end the central shaft 8 has a diametral hole, and a similar hole is provided in the hub 5, which hole is engaged by a pin 15 (FIG. 4) which also traverses a core 16 freely mounted on the hub 5. The inner end of a main spring 17 is hooked to one end of the pin 15, whereas its outer end is attached to the wall of a cap 18 fixed to the lower pillar plate 2 and constituting a stationary barrel. The inner end of the spring 17 is provided with a hole simply engaged by the end of the pin 15. Near its outer end the spring 17 has a narrower portion 19 (FIGS. 2 and 4) bearing against the edges of a rectangular opening of the cap 18, thus fixing the outer end of the spring 17 to the said cap 18. In order to hook the outer end of the spring 17 to the cap 18, it suffices to turn said end by 90°, to engage it in the opening of the cap 18 and to bring back said spring end into its initial position.

The cap 18 is secured to the lower pillar plate 2 by two lugs or bent portions 20 of the plate 2, bearing against a flange 21 of the cap 18, and by a rivet 22 fitted in the plate 2 and biting the flange 21 of the cap 18. There will be explained later how the cap 18 is put in place and fixed.

In the position illustrated in FIG. 3 the toothed sector 4 is in mesh with a pinion 23 rigidly fixed to an alarm wheel 24 which actuates a hammer 25 provided with two teeth 26. The hammer 25 carries a block 27 adapted to strike against a bell described later on.

At the right of and below the driving member 4 (FIG. 3) is arranged the train of gears of the clockwork movement, including the gears 28 to 35, the wheel 35 being the escape wheel which actuates a spindle 36 carrying a balance wheel or vibrating disc 37. The spindle 36 is milled so as to show two teeth (FIG. 3), so that it can oscillate like an alarm hammer when the escape wheel 35 is rotated. The wheel 31 is loosely mounted on the spindle 38 of the pinion 30 and is pressed by means of a friction spring 39 bearing on the pinion 30 against a disc 40 rigidly fixed to the spindle 38. A thin washer 41 of plastic material is inserted between the wheel 31 and the disc 40. The pinion 30 and the wheel 31 are therefore interconnected by means of a friction coupling, so that the wheel 31 can, under certain conditions, remain at rest when the pinion 30 is rotated, i.e. when the driving member 4 is rotated. This friction coupling might also be provided at another place of the train of gears 28 to 35, for instance between the pinion 28 and the wheel 29.

The toothing of the sector 4 extends over about 180° (FIG. 3) and the outer tooth thereof, at each end of the sector 4, is preferably shortened in order to avoid a jamming or interference as the toothed sector 4 engages either one of the pinions 23 and 28.

The casing of the apparatus essentially consists of a combined back and caseband 42 and a bezel 43. The combined back and caseband 42, which is made for instance of plastic material, simultaneously forms the bell 45 against which the block 27 of the hammer 25 strikes on releasing of the alarm device. A finger 44 made integral with the back 42 and arranged within reach of the block 27 is surrounded by a metallic tube 45 (FIG. 3). On the other hand, a metallic stop 46 is embedded in the wall of the back 42, on the side of the block 27 remote from the finger 44. When the hammer 25 oscillates, its

block 27 alternately strikes against the finger 44, 45 and the stop 46. Since the hit surfaces are made of metal, a disintegration of the plastic material under the effect of the repeated shocks is avoided.

In superposed cut-out parts 47 of the pillar plates 1 and 2 are engaged two projections 48 of the back 42 (FIG. 3) so as to orient the frame of the apparatus with respect to the casing. The combined back and caseband 42 has a lug 49 provided with a hole 55 for fixing e.g. a small chain carrying a key-ring.

The upper pillar plate 1 which, as already said, has a diameter slightly greater than that of the lower pillar plate 2, rests with its edge on a shoulder 50 of the combined back and caseband 42 (FIG. 4). A washer 51 of plastic material covers the upper plate 1 in order to prevent moisture and dust from penetrating within the apparatus.

The bezel 43 bears a scale "0-15-30-45-60" indicating the minutes and extending over half its periphery. Between the numerals 0 and 45, the subdivisions are provided for every 5 minutes, whereas between the numerals 45 and 60, they are provided for every 3 minutes for checking the telephone calls. The bezel 43 has a vertical flange 52 which is calked on the outer wall of the combined back and caseband 42 (FIG. 4). The winding knob 10 has a diameter scarcely less than the inner diameter of the bezel 43, so that it closes the casing on its upper face.

Two circular openings 53, superposed to each other, are provided in the pillar plates 1 and 2. They enable the worker to observe the position of the hammer 25, 27 on assembling the apparatus, care having to be taken that the block 27 be disposed between the finger 44 and the stop 46 (FIG. 3). In addition, the lower opening 53 allows the finger 44 to pass. On the other hand, in order to reduce the cost price, the discs of metal obtained by making the openings 53 are fixed together and used for making the balance wheel 37.

The illustrated apparatus is assembled as follows:

The driving member 4 with its hub 5 and all the gears of the clockwork movement and of the alarm device are put in place between the pillar plates 1 and 2, and the pillar plates 1 and 2 are then fixed together by riveting of the pillars 3. The insulating washer 51 is then placed on the pillar plate 1 and the winding knob 10 is put in place by introducing its shaft 8 into the hub 5. On the lower projecting end of the hub 5 the core 16 is freely mounted and the pin 15 is pushed through the core 16, the hub 5 and the shaft 8, thus interlocking the winding knob 10 and the driving member 4 and maintaining the winding knob 10 in axial direction. The cap 18 is then seized, in which the main spring 17 has been previously arranged so that its outer end be fixed as described to the wall of the cap 18. As concerns the inner end of the spring 17, it forms a winding the diameter of which is less than the diameter of the core 16, so that if the cap 18 is put in place under the lugs 20 of the pillar plate 2 and turned in the clockwise direction of FIG. 2, the hole provided in the spring 17 near its inner end gets caught on the end of the pin 15. The cap 18 is now turned in the clockwise direction of FIG. 2, by means of a suitable tool engaging the generally rectangular opening 54 of the cap 18, so as to wind completely the spring 17, and then turned back over a fraction of one turn. The initial tension of the spring 17 is thus adjusted, so as to utilize the most favorable section of the winding diagram of the spring 17. The cap 18 is then fixed in the angular position obtained by placing the rivet 22 which, as already said, bites a portion of the diameter of the flange 21 of the cap 18. After this step, the bell 42 and the bezel 43 are put in place, and the flange 52 of the bezel 43 is calked on the bell 42.

It will be seen that the apparatus includes no screws at all for assembling its parts. All the parts are main-

tained by calking and riveting, which allows to manufacture an apparatus with a very low cost price.

The apparatus works as follows:

When the parts have the position illustrated, the apparatus is in its rest position, the spring 17 having an initial stress as explained above. For completely winding the spring 17, the winding knob 10 is seized and turned in the clockwise direction of FIG. 1 (direction of the arrow on the bezel 43) with respect to the bezel 43, until 5 the mark 12 arrives in front of the desired numeral of the scale of the bezel 43. During the first portion of this rotation, until the mark 12 arrives at the numeral "0" of the bezel 43, the toothed sector 4 is in mesh with the pinion 23 and, therefore, drives the alarm device. 10 The hammer 25 oscillates and its block 27 strikes against the bell 42. As soon as the mark 12 arrives at the numeral "0" of the bezel 43, the toothed sector 4 is disengaged from the alarm pinion 23 (the alarm signal is stopped) and engages the pinion 28 of the clockwork 15 movement. The further rotation of the winding knob 10 rotates the gear 28, 29 and the pinion 30, but the resistance presented by the train of gears of the clockwork movement prevents the wheel 31 from rotating, which is rendered possible by the friction coupling between the pinion 30 and the wheel 31. After having set the lapse 20 of time at the end of which the alarm signal should be produced, the winding knob 10 is released. Under the action of the spring 17, the driving member 4 actuates the train of gears 28 to 35 and causes the balance wheel 25 30 to oscillate. The winding knob 10 slowly rotates in the counter-clockwise direction of FIG. 1 and at the moment when the mark 12 arrives in front of the numeral "0" of the bezel 43, the toothed sector 4 is disengaged from the pinion 28 and engages the alarm pinion 23. 35 Through the intermediary of the alarm wheel 24, the hammer 25 is actuated and its block 27 strikes against the parts 44 and 46 of the bell 42. Since during the operation of the alarm device the toothed sector 4 is disengaged from the clockwork movement, the spring 17 can put forth all its strength for actuating the alarm device and impart to the sector 4 a speed which is much greater than before, so that the return movement of the mark 12 from the numeral "0" to the rest position illustrated, during which the alarm signal is produced, is made 45 in a very short time interval of about one or two seconds. As already said, the movement of rotation of the winding knob 10 is limited by the engagement of the lug 14 of the pillar plate 1 in the groove 13 of the knob 10. The described cycle can now begin again, the rest position of the parts being again reached.

When the apparatus has been set for a predetermined lapse of time, it is always possible to modify the setting by turning the winding knob 10 in the one or the other direction, although the toothed sector 4 is in mesh with the pinion 28, due to the friction coupling provided between the pinion 30 and the wheel 31.

For checking the telephone calls the mark 12 is placed on the numeral "60" of the scale of the bezel 43 and the winding knob 10 is released. When the telephone call is terminated, it suffices to read the position of the mark 12 for ascertaining the number of 3-minute intervals elapsed since the beginning of the conversation.

The apparatus described and illustrated is mainly used for checking the parking time of cars and other vehicles. 60 By modifying in an appropriate manner the clockwork movement, it would be possible to cause the apparatus to run for a maximum time different from 60 minutes.

What is claimed is:

1. In a time meter with alarm device, adapted to produce an alarm signal at the end of a predetermined lapse of time, including a clockwork movement and an alarm device arranged between two pillar plates, a driving member adapted to successively engage a part of the said clockwork movement and a part of the said alarm device,

a single main spring arranged outside the frame formed by the said pillar plates and a rotary winding knob, coaxial with the said driving member, serving to wind the main spring and to set the said lapse of time, the outer end of the main spring being attached to one of the said pillar plates, the winding knob being rigidly connected to a shaft and the driving member being rigidly secured to a hub, the improvement in which the inner end of the main spring is hooked to a pin traversing the shaft of the winding knob and the hub of the driving member, the said pin thus interlocking the said shaft and the said hub and also interlocking, therefore, the winding knob and the driving member and securing the winding knob in axial direction.

2. A time meter with alarm device as claimed in claim 1, in which the said driving member consists of a toothed sector.

3. A time meter with alarm device as claimed in claim 1, in which, before the insertion of the said pin, the shaft of the winding knob is freely mounted within the hub of the driving member.

4. A time meter with alarm device as claimed in claim 1, in which the winding knob has on its lower face a groove extending over almost its whole periphery, which groove is engaged by a stop rigidly connected to the frame, in order to limit the movement of rotation of the winding knob.

5. In a time meter with alarm device as claimed in claim 1, in which the outer end of the main spring is attached to a cap secured to one of the pillar plates, the improvement in which the said cap is maintained on the

frame by two lugs integral with one of the said pillar plates and by a rivet fitted into said pillar plate and biting a flange of the cap.

6. In a time meter with alarm device as claimed in claim 1, comprising a combined back and caseband made of plastic material, simultaneously forming a bell for the alarm device, said bell carrying a finger made of one piece therewith, adapted to be hit by an alarm hammer, the improvement in which the said finger is surrounded by a metallic tube, and a metallic stop is embedded in the said bell, so that when the hammer oscillates, it strikes alternately against the said finger and the said stop without disintegrating the plastic material of the bell.

7. A time meter with alarm device as claimed in claim 1, in which a washer covers the upper plate, in order to prevent moisture and dust from penetrating within the time meter.

8. A time meter with alarm device as claimed in claim 1, comprising a combined back and caseband, in which a bezel carrying a scale on a portion of its circumference surrounds the winding knob and is fixed to the said combined back and caseband.
